FIG. 1 is a perspective view of a muscle arm float, showing
our new design;

FIG. 2 is an enlarged front elevational view thereof;

FIG. 3 is a left-side elevational view thereof, the right-side
elevational view being a mirror image thereof;

FIG. 4 is a rear elevational view thereof;

FIG. 5 is a top plan view thereof; and,

FIG. 6 is a bottom plan view thereof.

The broken lines showing a child and an additional arm float
in FIG. 1, and an inflation port in the figures depict environ-
mental matter and form no part of the claimed design.
